UNITED STATES PATENT OFFICE

HENRY HENRICH, OF NEW YORK, N. Y., ASSIGNOR TO HIMSELF AND
ROBERT HEERBRANDT, OF SAME PLACE.

DESIGN FOR A BUTTON.

Specification forming part of Design No. **6,013**, dated July 30, 1872.

Specification describing new and original Design for Buttons, Studs, Lockets, &c., invented by HENRY HENRICH, of the city, county, and State of New York.

In the accompanying drawing, Figure 1 represents my improved design as applied to a locket. Fig. 2 represents the same design applied to a button. Fig. 3 is a detail section taken through the line $x x$, Fig. 2, showing the form of the parts.

My invention has for its object to furnish an improved design for buttons, studs, lockets, &c., which shall be simple, neat, chaste, and beautiful, and will impart to the article to which it may be applied a rich and elegant appearance; and it consists in the design hereinafter more fully described.

The general form of the design is oval or circular, as shown in Figs. 1 and 2.

A is the rim, frame, or base of the article, the outer surface of which is inclined or beveled, as shown in Fig. 3. The inner side or

surface of the rim A is straight or at right angles with the plane of said rim, and has an inwardly-projecting shoulder or flange, B, formed upon it. C is the center piece, which is made convex, as shown in Figs. 1, 2, and 3. With this form the center piece has a deep cavity or channel all around it, as shown in the drawing. The rim A is designed to be made of gold of the ordinary color, the center piece C of yellow gold, and the shoulder or flange B, or a flat ring placed upon said shoulder or flange, of yellow gold, so as to obtain a contrast of color, increasing the effect of the design.

I claim as my invention—

The design for buttons, studs, lockets, &c., herein shown and described.

HENRY HENRICH.
